UNITED STATES PATENT OFFICE.

NICHOLAS S. VEDDER AND FRANCIS RITCHIE, OF TROY, NEW YORK, AS
SIGNORS TO NICHOLAS S. VEDDER, OF SAME PLACE.

DESIGN FOR A RANGE.

Specification forming part of Design No. 6,312, dated December 17, 1872.

To all whom it may concern:

Be it known that we, NICHOLAS S. VEDDER and FRANCIS RITCHIE, each of the city of Troy, in the county of Rensselaer and State of New York, have jointly invented and produced a new and original Design for Ranges, of which the following is a specification, reference being had to the accompanying wood cut or engraving of a range having our said design.

One part of our invention consists of the compound ornament K, shaped and arranged on a door or panel of a stove or range as shown in the wood-cut. Another part consists of the ornament L, shaped and arranged on a door or panel of a stove or range as shown in the engraving. Another part consists of the compound ornamental border molding or moldings M, shaped and arranged along the edge or edges of a door or doors or panel or panels of a stove or range so as to appear as represented in the engraving. Another part consists of the ornament or ornaments n or o, shaped and arranged on a door or doors or panel or panels of a stove or range as shown in the wood-cut. Another part consists of the combination of the ornamented molding or moldings M and central panel ornament or

ornaments K or n or o, as shown in the engraving, with or without the ornament L. Another part consists of the design for the side plate P and end plate Q, as distinguished by the chain ornamentation r having angular links, and shaped and arranged as shown in the cut.

What we claim as our invention is—

1. The compound panel-ornament K, shaped and arranged as herein described.
2. The panel-ornament L, shaped and arranged as shown and described.
3. The compound ornamented border molding or moldings M, shaped and arranged as herein set forth.
4. The compound panel ornament or ornaments n or o, shaped and arranged as herein set forth.
5. The design for the combination of the molding or moldings M and panel ornament or ornaments K or n or o, as herein set forth.
6. The design for the side and end plates P Q, as herein set forth.

NICHOLAS S. VEDDER.
FRANCIS RITCHIE.
